TRASH RAKE

Thoralf K. Breda, York, Pa., assignor to S. Morgan Smith Company, York, Pa., a corporation of Pennsylvania

Application July 20, 1946, Serial No. 685,085

9 Claims. (Cl. 210—176)

1

This invention relates to new and useful improvements in rakes, and more particularly to rakes for removing debris from a trash rack or grating across the intake end of a mill race, sluiceways, and the like.

In trash rakes existing prior to the present invention it is quite difficult, if not impossible, to thoroughly clean the lower portion of the trash rack through which a free flow of water is very important. This lower portion of the rack frequently is obstructed by a tough interwoven mass of twigs, grasses, reeds and the like, compacted by the pressure of the water and seriously restricts the flow of water through the rack. This tough interwoven mass usually forms an inclined bank against the rack at the upstream side thereof with the result that the rake, as it is lowered upon the rack, rides outwardly or away from the rack upon the surface of the bank of matted material and the teeth of the rake cannot reach the debris and material at the bottom of the bank to remove it.

With the foregoing in mind, one object of the present invention is to provide a trash rake of the character set forth having a novel auxiliary rake structure arranged to reach and engage the bottom portion of a bank of interwoven debris at the lower part of a trash rack.

Another object of the invention is to provide a trash rake of the stated type having primary teeth positionable in operative and inoperative positions which is provided with auxiliary rake structure movable into operative and inoperative positions according to the positioning of the primary teeth of the rake.

A further object of the invention is to provide a trash rake embodying the described construction and arrangement having novel means operable to control the position of the auxiliary rake structure according to the position of the primary teeth of the rake.

A further object of the invention is to provide a trash rake of the character set forth having an auxiliary rake structure constructed and arranged so that it will be deflected outwardly to travel downwardly over the inclined surface of a bank of debris at the lower portion of a trash rack to the bottom thereof in position to dig into and engage the debris at the bottom of the bank upon initiation of upward travel of the trash rake.

A still further object of the present invention is to provide a novel trash rake device having the features and advantages set forth which is of relatively simplified and inexpensive construc-

2

tion, and entirely foolproof and efficient in operation and use.

These and other objects of the invention and the various features and details of construction and operation thereof are hereinafter fully set forth and described with reference to the accompanying drawings; in which:

Fig. 1 is an elevational view of a trash rake installation embodying a rake made according to the present invention.

Fig. 2 is a partial view similar to Fig. 1 illustrating certain operating features of the present rake.

Fig. 3 is a front elevational view of a trash rake embodying the present invention.

Fig. 4 is an enlarged sectional view taken on line 4—4, Fig. 3; and

Fig. 5 is an enlarged sectional view taken on line 5—5, Fig. 3.

Referring now more particularly to the drawings, a conventional trash rack comprises a series of inclined, equally spaced, parallel bars 2 arranged to provide a grill- or grating-like arrangement which acts as a barrier to arrest and collect trash and debris which otherwise would be carried through the race, sluiceway, or the like.

The improved trash rake of the present invention is constructed for use in conjunction with a rack of the type described to remove from time to time the trash and debris which is collected on the rack and, in the illustrated embodiment thereof, includes a rectangular frame comprising relatively spaced-apart end or side plates 3 between which extend top and bottom horizontal members 4 and 5, respectively, the latter being additionally connected together and supported by means of a plurality of spaced parallel bars or the like 6 arranged intermediate said end or side plates 3.

Extending between the end or side plates 3 of the rake and parallel to and adjacent the horizontal frame member 5 is a shaft 7 having reduced end portions 7a that extend through and are rotatably supported in the said side plates 3, for example, in the manner shown in Fig. 5 of the drawings. Carried by the shaft 7 are a plurality of rake teeth 8 which may be fixedly secured to said shaft in any suitable manner.

For example, the shaft 7 may be of tubular construction for the advantage of lightness and the rake teeth 8 may be inserted through openings provided in said shaft and secured thereto by means of welding or the like.

Rotation of the shaft 7 is limited to approx-

imately 90 degrees and the teeth 8 are secured in or to the shaft 7 so that in one limit position thereof said teeth are disposed in the position shown in Fig. 2 of the drawings, and in the other limit position of the shaft are disposed in the position shown in Figs. 1 and 4 of the drawings. Limitation of the extent of rotation of the shaft 7 may be effected in the manner illustrated in the drawings by providing on one or both end portions 7a of the shaft 7 a fixed projection or pin 9 which moves therewith within an arcuate slot 10 formed in the side plates 3. The arcuate slot 10 is shaped substantially to the quadrant of a circle and hence movement of the pin 9 therein serves positively to limit rotational movement of the shaft 7 and its teeth 8 to about 90 degrees between the position shown in Fig. 2 wherein the said teeth 8 are disposed parallel to the rack bars 2 and the position shown in Fig. 1 wherein the teeth 8 are disposed perpendicular to said bars 2 and project a short distance inwardly therebetween.

Rotationally mounted upon the extremities of the reduced end portions 7a of the shaft 7 are wheels 11 whose peripheries are adapted to run or ride upon certain of the rack bars 2, 2 of the trash rack. Preferably the peripheries of the wheels 11 are provided with a continuous narrow rib or flange 12 which serves to limit lateral displacement of the rake with respect to the rack when the teeth 8 are in the inoperative position of Fig. 2.

The wheels 11 operate to effect rotation of the shaft 7 within the limits permitted by the slot 10 and pin 9 and this is accomplished by friction means carried by said wheels. Thus, each of the wheels 11 is provided with one or more radial bores or passages 13 therein which extend inwardly to the shaft end portions 7a, and disposed within such bores or passages 13 are elements 14 of friction material, for example, lignum vitae which engage against the surface of the end portions 7a of the shaft under the pressure of springs 15. Suitable plugs 16 are threaded into the passages 13 to retain therein the friction elements 14 and springs 15, and the plugs 16 may be adjusted as required to vary the pressure exerted by springs 15 upon the friction elements 14 to cause the latter to engage the shaft end portions 7a with sufficient force or pressure to provide the necessary drive connection between the wheels 11 and shaft 7.

With the friction assemblies in the wheels 11 properly adjusted, it will be apparent that as the rake is lowered upon the rack from an elevated position, the wheels 11 on the bars 2 will rotate in the clockwise direction with respect to Figs. 1 and 2 of the drawings with the result that the friction elements 14 cause the shaft 7 to rotate with said wheels 11 in that same direction to the extent permitted by the pin 9 moving within the slot 10 thereby positioning the rake teeth 8 in the inoperative position shown in Fig. 2, the shaft and teeth being maintained in this position by the drag of the friction elements 14 so long as lowering movement of the rake and accompanying clockwise rotation of the wheels 11 continues.

On the other hand, when the rake has been lowered the required distance and commences to rise or move upwardly upon the rack bars 2, thereby rotating the wheels 11 in the counterclockwise direction with respect to Fig. 1 of the drawing, the friction elements 14 will operate immediately to cause the shaft 7 and its teeth 8 to be rotated into the position shown in Fig. 1 so as to dig into and

engage debris on the rack during initial upward movement of the rake.

As previously stated it is the lower portion of the trash rack through which a free flow of water is very important and hence it is highly desirable that the lower portion of the rack be thoroughly cleaned from time to time to remove the tough inter-woven mass of twigs, grasses, reeds and the like, which collect and are compacted against the rack by the pressure of the water and seriously restrict the flow of water through the rack. This mass is usually in the form of an inclined bank such as indicated at A in Fig. 2 of the drawings which bears on the lower portion of the upstream side of the rack, and its presence causes the rake, as it is lowered, to ride outwardly or away from the rack upon the surface of the bank of matted material as indicated in Fig. 2 and the teeth of the rake cannot reach the debris at the bottom of the bank to remove it and effectively clean the lower portion of the rack.

To overcome this disadvantage, the trash rake of the present invention embodies an auxiliary rake structure including a frame 17 comprising side frame members 18 and a cross-frame member 19 to which is secured a plurality of teeth 20 arranged as shown in the drawings. The frame 17 has its side members 18 pivotally connected at their free ends to rake side plates 3 as indicated at 21. It is to be observed that the side frame members 18 of the pivoted frame 17 are considerably longer than the rake side plates 3 so that the cross-member 19 and its teeth 20 are disposed an appreciable distance below or beyond the teeth 8 on the shaft 7 and relatively remote from the rake wheels 11.

Secured to and carried by each of the side frames 18 is a plate 22 arranged for engagement by a cam member 23 which is keyed or otherwise fixedly secured upon the reduced ends 7a of the shaft 7 intermediate the wheels 11 and the rake side plates 3 as shown, for example, in Fig. 5 of the drawing. The cam 23 is secured rotationally of the shaft 7 and is configurated or shaped so that when the said shaft and its teeth 8 are in the operative or raking position shown in Fig. 4 and in Fig. 1, the low portion of the cam 23 is presented to the plate 22 with the result that the auxiliary rake likewise is in the operative or raking position. On the other hand, when the shaft 7 and its teeth 8 are in the inoperative position and parallel to the rack bars 2, the cams 23 will operate to pivot the auxiliary rake outwardly into the position shown in dotted lines in said Fig. 1 so that it is substantially removed from possible engagement with debris packed against the rack as the rake is lowered thereon and furthermore will be in a position so that it may easily be deflected still further outwardly by the material of the bank A as the rake approaches the bottom of the rack and rides onto the bank as shown. In addition, by reason of the fact that the teeth 20 of the auxiliary rake are disposed well below the teeth 8 and remote from the wheels 11, the teeth 20 can reach the debris at the bottom of the bank, and will dig into and engage the debris upon initial upward movement of the rake.

The rake can be used on existing racks without change of the racks, and may be operated by means of a suitably driven hoist 24, for example, through a pair of suitable flexible cables 25 connected to opposite ends of the upper edge of the rake by means of shackles or the like 26. In accordance with one conventional practice the

hoist 24 may be mounted upon a suitable frame structure F having suitable extension rails 2a adapted to be positioned in alignment with the bars 2 on which the rake moves so that the rack may be raised to the usual elevated position above the rake for the purpose of discharging the trash and debris removed from the rack by the rake.

In addition, and in order to insure actuation of the primary and auxiliary teeth 8 and 20 into their described inoperative positions upon downward travel of the rake in the event that the friction assemblies in the wheels may not function properly, there may be associated with the stationary rack structure a pivotally mounted finger or the like 21. This finger 21 normally is disposed in the path of one of the rake teeth 8 by a spring 28 which embraces a rod 29 that is pivotally connected to the said finger 21 and slidably supported by a bracket 30. The spring 28 acts between the bracket 30 and a collar 31 on the rod 29 to permit the finger to be actuated counter-clockwise out of the way by the tooth 8 upon upward travel of the rake, for example, to the broken line position shown in Fig. 1 and then automatically return said finger to the operative position shown for engagement by the tooth 8 as the rake moves down the rails 2a onto the rack, whereby the teeth 8 and the auxiliary rake structure are inoperatively positioned in the event that they have not already been so positioned by the friction assemblies in the wheels. A stop 32 serves to prevent return or clockwise movement of the finger 21 beyond the operative position shown in Fig. 1 of the drawings.

From the foregoing it will be apparent that the present invention provides a trash rake of the character set forth having a novel auxiliary rake structure arranged to reach and engage the bottom portion of a bank of debris at the lower portion of a trash rake. The invention also provides a trash rack having primary teeth positionable in operative and inoperative positions together with an auxiliary rake structure which is movable into operative and inoperative positions according to the positioning of the primary teeth of the rake and which is deflectable outwardly to travel downwardly over the inclined surface of a bank of debris in position to dig into and engage the debris at the bottom of the bank upon initiation of upward movement of the rake. Furthermore, the invention provides a novel trash rake device having the features and characteristics set forth which is of relatively simplified and inexpensive construction, and entirely foolproof and efficient in operation and use.

While a particular embodiment of the present invention has been illustrated and described herein, it is not intended that the invention be limited to such disclosure, and changes and modifications may be made therein and thereto within the scope of the claims.

I claim:

1. In a trash rake, a frame, a member rotatably carried by said frame, wheels on said member supporting said frame for travel up and down a trash rack, a first set of teeth carried by said member, said member being shiftable by rotation of said wheels in one direction to an operative position in which said teeth are disposed substantially perpendicular to said frame and in the other direction of rotation of said wheels to an inoperative position in which said teeth are disposed substantially parallel to said frame, means

interposed between said wheels and member operable normally to shift the latter to said inoperative position upon downward travel of the rake and to said operative position upon upward travel thereof, an auxiliary rake structure including side members pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and cam means carried by said member and engaging the side members of said auxiliary rake structure to pivot the same to said operative and inoperative positions according to the positioning of said first set of teeth.

2. In a trash rake, a frame, a shaft journaled in said frame and rotatable between fixed limit positions, wheels on the ends of said shaft supporting the same and said frame for travel up and down a trash rack, a first set of teeth carried by said shaft and arranged circumferentially thereof so that in one limit position of the shaft said teeth are disposed in an operative position substantially perpendicular to said frame and in the other limit position of the shaft are disposed in an inoperative position substantially parallel to said frame, friction clutch means connecting said wheels and shaft operable normally to cause said shaft to rotate with said wheels and inoperatively position said teeth upon downward travel of the rake and operatively position said teeth upon upward travel thereof, an auxiliary rake structure pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and means carried by said shaft and engaging the auxiliary rake structure to pivot said auxiliary rake structure to said operative and inoperative positions according to the positioning of said first set of teeth.

3. In a trash rake, a frame, a shaft journaled in said frame, wheels on the ends of said shaft supporting the same and said frame for travel up and down a trash rack, a first set of teeth carried by said shaft and movable therewith between an operative position in which said teeth are disposed substantially perpendicular to said frame and an inoperative position in which said teeth are disposed substantially parallel to said frame, means normally operable to establish a driving connection between said wheels and said shaft to rotate the latter with said wheels and inoperatively position said teeth upon downward travel of the rake and operatively position said teeth upon upward travel thereof, an auxiliary rake structure pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and means on said shaft and engaging said auxiliary rake structure to pivot the same to said operative and inoperative positions according to the positioning of said first set of teeth.

4. In a trash rake, a frame, a shaft journaled in said frame, wheels on the ends of said shaft supporting the same and said frame for travel

up and down a trash rack, a first set of teeth carried by said shaft, means limiting rotation of said shaft between an operative position in which said teeth are disposed substantially perpendicular to said frame and an inoperative position in which said teeth are disposed substantially parallel to said frame, means operable normally to cause said shaft to rotate with said wheels and inoperatively position said teeth upon downward travel of the rake and operatively position said teeth upon upward travel thereof, an auxiliary rake structure including side members pivoted to said frame and movable between an operative position substantially coplanar with said frame and an inoperative position angularly outward therefrom, a second set of teeth carried by said auxiliary rake structure and arranged parallel to and substantially spaced from said first set of teeth, and cam means on said shaft engaging the side members of said auxiliary rake structure to pivot the same to said operative and inoperative positions according to the positioning of said first set of teeth.

5. In a trash rake, a frame, wheels supporting said frame for travel up and down a trash rack, a first set of teeth, a member rotatably carried by said frame with its rotational axis parallel to the trash rack and mounting said first teeth so that the latter are disposed perpendicular to said axis, said member being rotationally shiftable between an operative position in which said teeth are disposed substantially perpendicular to said rack and an inoperative position in which said teeth are disposed substantially parallel to said rack, connections between said wheels and said member operable normally to shift said member to said inoperative position upon downward travel of the rake and to said operative position upon upward travel thereof, an element associated with the trash rack adjacent the upper end thereof and normally disposed in the path of travel of one of said first set of teeth in the operative position thereof and arranged for engagement by said tooth to actuate the first set of teeth to said inoperative position thereof upon downward travel of the rake, an auxiliary rake structure pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and means carried by said member and engaging said auxiliary rake structure to pivot said rake structure to said operative and inoperative positions according to the positioning of said first set of teeth.

6. In a trash rake, a frame, wheels supporting said frame for travel up and down a trash rack, a first set of teeth, a member rotatably carried by said frame with its rotational axis parallel to the trash rack and mounting said first teeth so that the latter are disposed perpendicular to said axis, said member being rotationally shiftable between an operative position in which said teeth are disposed substantially perpendicular to said frame and an inoperative position in which said teeth are disposed substantially parallel to said rack, connections between said wheels and said member operable normally to shift said member to said inoperative position upon downward travel of the rake and to said operative position upon upward travel thereof, a pivoted finger associated with the trash rack adjacent the upper

end thereof and normally disposed in the path of travel of one of said first set of teeth in the operative position thereof and arranged for engagement by said tooth to actuate the first set of teeth to said inoperative position thereof upon downward travel of the rake, spring means biasing said finger normally into the path of said tooth for engagement thereby, an auxiliary rake structure pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and means carried by said member and engaging said auxiliary rake structure to pivot said rake structure to said operative and inoperative positions according to the positioning of said first set of teeth.

7. In a trash rake, a frame, a shaft journalled in said frame and rotatable between fixed limit positions, wheels on the ends of said shaft supporting the same and said frame for travel up and down a trash rack, a first set of teeth carried by said shaft and arranged circumferentially thereof so that in one limit position of the shaft said teeth are disposed in an operative position substantially perpendicular to said frame and in the other limit position of the shaft are disposed in an inoperative position substantially parallel to said frame, friction clutch means connecting said wheels and shaft operable normally to cause said shaft to rotate with said wheels and inoperatively position said teeth upon downward travel of the rake and operatively position said teeth upon upward travel thereof, an element associated with the trash rack adjacent the upper end thereof and normally disposed in the path of travel of one of said first set of teeth in the operative position thereof and arranged for engagement by said tooth to actuate the first set of teeth to said inoperative position thereof upon downward travel of the rake, an auxiliary rake structure pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and means carried by said shaft and engaging the auxiliary rake structure to pivot said auxiliary rake structure to said operative and inoperative positions according to the positioning of said first set of teeth.

8. In a trash rake, a frame, a shaft journalled in said frame, wheels on the ends of said shaft supporting the same and said frame for travel up and down a trash rack, a first set of teeth carried by said shaft, means limiting rotation of said shaft between an operative position in which said teeth are disposed substantially perpendicular to said frame and an inoperative position in which said teeth are disposed substantially parallel to said frame, means operable normally to cause said shaft to rotate with said wheels and inoperatively position said teeth upon downward travel of the rake and operatively position said teeth upon upward travel thereof, a pivoted finger associated with the trash rack adjacent the upper end thereof and normally disposed in the path of travel of one of said first set of teeth in the operative position thereof and arranged for engagement by said tooth to actuate the first set

of teeth to said inoperative position thereof upon downward travel of the rake, spring means biasing said finger normally into the path of said tooth for engagement thereby, an auxiliary rake structure including side members pivoted to said frame and movable between an operative position substantially coplanar with said frame and an inoperative position angularly outward therefrom, a second set of teeth carried by said auxiliary rake structure and arranged parallel to and substantially spaced from said first set of teeth, and cam means on said shaft engaging the side members of said auxiliary rake structure to pivot the same to said inoperative position upon downward travel of the rake and to said operative and inoperative positions according to the positioning of said first set of teeth.

9. In a trash rake, a frame, wheels supporting said frame for travel up and down a trash rack, a first set of teeth, a member rotatably carried by said frame with its rotational axis disposed parallel to the trash rack and mounting said first set of teeth so that the latter are disposed perpendicular to said axis, connections between said wheels and member operable upon downward travel of the rake to shift said member to an inoperative position in which said teeth are disposed substantially parallel to the rack and upon

upward travel of the rake to shift said member to an operative position in which said teeth are disposed substantially perpendicular to the rack, an auxiliary rake structure pivoted to said frame and movable relative thereto between an operative position substantially coplanar with said frame and an inoperative position angularly outward therefrom, a second set of teeth carried by said auxiliary rake structure and arranged parallel to and substantially spaced from said first set of teeth, and means carried by said member and engaging said auxiliary rake structure to pivot said rake structure to said inoperative position upon downward travel of the rake and to said operative and inoperative positions according to the positioning of said first set of teeth.
